TYPEWRITER

William H. Schmidt, Wauwatosa, Wis.

Application March 9, 1936, Serial No. 67,945

4 Claims. (Cl. 197—153)

This invention appertains to typewriting machines, and more particularly to novel means for producing copies on such machines.

It is now customary to utilize carbon paper between the original sheet and the copy or copies to be made. The handling of the carbon paper is objectionable, and much time is expended by the typist in placing and removing the carbon into and out of operative position, and the copy or copies made are of a different character than the original.

Therefore, one of the primary objects of my invention is to provide multiple ribbons for producing the copies, whereby the use of carbon paper or other extraneous duplicating means is entirely eliminated, and whereby the copy or copies made will have substantially the same appearance as the original.

Another object of my invention is to provide a series of parallel ribbon stretches on the typewriter in front of the platen roller, so that a sheet can be placed in rear of each ribbon stretch for making the original and the duplicates, with means for feeding the ribbon stretches across the sheets in unison during the operation of the typewriter.

Another salient object of my invention is the provision of means for so arranging and disposing the ribbon stretches that the marking on both sides of the paper sheet by the ink on the ribbon will be prevented.

A further object of my invention is the provision of novel means for utilizing a series of independent ribbon on a typewriter, whereby the original and duplicate copies can be conveniently and expeditiously made.

A further important object of my invention is to provide novel means for forming the ribbons themselves, whereby the ink on the ribbon will not be transferred to the opposite faces of a sheet of paper.

A still further object of my invention is to provide an improved means for making duplicate copies on a typewriter, which will be durable and efficient in use, one that will be simple and easy to manufacture, and one which can be incorporated with a typewriter at a small cost.

With these and other objects in view, the invention consists in the novel construction, arrangement, and formation of parts, as will be hereinafter more specifically described, claimed, and illustrated in the accompanying drawings, in which drawings:

55. Figure 1 is a top plan view illustrating a type-

writer diagrammatically, showing one form of my invention applied thereto.

Figure 2 is an enlarged, detail vertical section taken substantially on the line 2—2 of Figure 1, illustrating the guide employed for the ribbon 5 stretches.

Figure 3 is a similar view, illustrating a slightly modified form of guide.

Figure 4 is a fragmentary vertical section through the platen roller of a typewriter and 10 associate parts, illustrating the guide for the ribbon.

Figure 5 is a fragmentary, longitudinal sectional view taken substantially on the line 5—5 of Figure 1, illustrating the tension and slack take- 15 up roller for the ribbon.

Figure 6 is a diagrammatic view in top plan, illustrating the use of a ribbon inked on one side only.

Figure 7 is a fragmentary top plan view illus- 20 trating a typewriter diagrammatically, showing another form of my invention in which the ordinary typewriter ribbon is utilized in conjunction with an independent ribbon.

Figure 8 is a fragmentary, top plan view illus- 25 trating the use of two ribbons carried by the same spools, the view being of a diagrammatic nature.

Figure 9 is a view similar to Figure 8, but showing the spools carried by the frame of the typewriter.

Figure 10 is a perspective view of a preferred 30 type of guide for the ribbon stretches.

Referring to the drawings in detail, wherein similar reference characters designate corresponding parts throughout the several views, the 35 letter T generally indicates a typewriter, which can be of any preferred type or make.

Thus, the typewriter is of the usual construction and includes the frame 15 having the keyboard 16 and the reciprocating carriage 17 carrying the rotatable platen roller 18. In front of the platen roller 18 is arranged the spaced ribbon guides 19, between which the type keys 20 are adapted to strike. On each side of the ribbon guides 19 are mounted the usual ribbon 40 spools 21 and 22 which are turned in the ordinary manner during the operation of the keys 20 and the typewriter carriage.

In the present instance, the spools 21 and 22 45 are not utilized for carrying the ribbon, but act 50 as a feed mechanism, as will be later set forth.

In accordance with my invention, I utilize an endless ribbon 23, and this ribbon can be of substantially the ordinary character, that is, the ink extends through the opposite faces thereof.

- An intermediate portion of the ribbon is fed through the guides 19 to form a front ribbon stretch 24, and over the spools 21 and 22. The ends of the ribbon 23 are trained over guide rollers 25 and 26 and over small guide rollers 27 and 28 mounted on the carriage 17. The small guide rollers 27 and 28 are arranged at the opposite ends of the platen roller 18 in front thereof, so that a rear ribbon stretch 29 will be provided.
- 10 The end roller 26 is rotatably supported by a bracket 30 rigidly connected with the frame 15 of the typewriter. The roller 25 is rotatably supported by a U-shaped yoke 31, slidably mounted on a bracket 32 rigidly secured to the frame of the typewriter. An expansion spring 33 is disposed between the yoke 31 and the typewriter frame, so as to normally urge the yoke and the roller outwardly, and thereby create a tension on the ribbon to take up slack therein.
- 15 20 I provide a novel guide for the rear stretch 29 of the ribbon, and this guide is adapted to extend the full length of the carriage in front of the roller 18. The guide can be in the nature of a flattened tube 34, and the terminals thereof are secured to the carriage in any preferred manner, such as by brackets 35. The opposite sides of the guide tube 34 are provided with slots 36, so that as the ribbon stretch 29 is fed through the tube, a typewriter key actuated by the operator can 25 make the desired impression. Obviously, the ribbon contacting with the spools 21 and 22 will be automatically fed thereby through the tube.

In use of my improved appliance, the original paper sheet 37 is placed in rear of the front ribbon stretch 24 and in front of the guide tube 34, and the copy 38 is placed in rear of the guide 34. Obviously, the original and duplicate sheets 38 are threaded into the typewriter in the usual manner, that is, between the platen roller 18 and 30 the guide aprons 39 and 40.

It is preferred to mount and form the ribbon guide 34 in a novel manner, so that the same will also function as a separator for the sheets 37 and 38. Thus, by referring to Figure 10, it can 45 be seen that the guide 34 can have formed thereon rearwardly extending arcuate fingers 41, which extend under the platen roller 18. These fingers 41 can be formed on a rear bar 42, and the terminals of the rear bar 42 can be provided with laterally extending, rearwardly directed feet 43, which can be riveted or otherwise secured to the carriage.

In order to prevent the marking of the opposite sides of the original sheet 37 by the ribbon stretches 24 and 29, the inner face of the front wall of the guide tube 34 can have attached thereto a thin piece of material 44, which may be cellophane. If desired, the upper end of the guide tube 34 may be left open, as at 45. This 55 is clearly shown in Figure 3 of the drawings. By leaving the guide 34 open at its top, the placing of the ribbon in the guide is facilitated.

I can eliminate the use of the cellophane strip 44, if the same proves objectionable, and in this 60 instance, I can provide a ribbon 46 (see Figure 6). This ribbon 46 is only impregnated with ink on one side, and the other side or face of the ribbon can be treated with some material, such as wax, which is impervious to ink. In this instance, it 65 will be necessary to twist the ribbon at right angles, as indicated by the reference character 47, on opposite sides of the spools 21 and 22.

If preferred and desirable, I can utilize an ordinary typewriter ribbon 48, as is illustrated in Figure 7 of the drawings. In this instance, the

ribbon 48 is paid on and off the usual spools 49 and 50. In conjunction with the ribbon 48, I utilize a separate endless ribbon 51. The front stretch 52 of the ribbon 51 is arranged in rear of the ribbon 48 and directly in front of the 5 platen roller 53. This stretch 52 may be held in proper position and fed through a guide of the same type and character as that shown in Figure 10. The ends of the ribbon 51 are trained over the rollers 54 and 55, which can be of the same 10 character as the rollers 25 and 26.

To permit the feeding of the ribbon 51, the same is trained over a feed roller 56. This roller 56 is rotatably mounted on a supporting stub shaft 57 carried by the frame of the typewriter, 15 and the roller has formed thereon or secured thereto a pinion 58, which meshes with a rack bar 59 carried by the rear face of the carriage. Thus, during the travel of the carriage, the roller 56 will be turned so as to feed the ribbon.

In Figure 8 of the drawings, I have illustrated another form of my invention. In this form, I utilize a pair of ribbons 60 and 61, which are fed off and on the same typewriter spools 62 and 63. These spools 62 and 63 are rotatably mounted 25 on pins 64 carried by ears 65 formed on or secured to the front corners of the carriage 66 of the typewriter. The ribbons 60 and 61 can be formed similar to the ribbon 46, that is, the same are only provided with ink on their rear faces. The 30 ribbons 60 and 61 are provided with parallel stretches 67 and 68 respectively, which extend the full length of the platen roller 69, and suitable guides 70 are provided for the stretches. The spools 62 and 63 are operated in the usual manner. In this form of my invention, the original and duplicate sheets are placed in the typewriter in the same manner as in the form first described.

In Figure 9, I have illustrated another form of my invention, which is similar to that form 40 shown in Figure 8 of the drawings. The main difference is that I provide spools 71 and 72 for the ribbons 73 and 74, and the spools are carried by brackets 75 and 76, which are secured to the frame of the machine instead of on the 45 carriage.

While I have only shown two ribbons in Figures 8 and 9, it is to be understood that I can use as many ribbons on the spools as may be desired, so that more than one copy can be made at the time 50 of the making of the original.

From the foregoing description, it can be seen that I have provided an exceptionally simple and durable means carried directly by the typewriter for making duplicate copies without the necessity 55 of providing extraneous devices, such as carbon paper.

By using two or more ribbons, a clear impression can be made on the duplicate copy, which will be similar to the original and not bear any resemblance to the ordinary copy made when carbon paper is employed.

Changes in details may be made without departing from the spirit or the scope of my invention, but what I claim as new is:

1. The combination with a typewriter including a frame, a reciprocating carriage on said frame, a platen roller rotatably mounted upon the carriage, spaced ribbon guides on said carriage, and feed and take-up spools on the frame, of 70 means for making an original and a duplicate copy on the typewriter including an endless ribbon, guide rollers for the ends of said ribbon, one of said rollers being spring-pressed, a longitudinally extending ribbon guide mounted upon said 75

- carriage in front of the platen roller and in rear of the first mentioned ribbon guides, the ribbon including front and rear stretches, the front stretch being threaded through the first mentioned guides and around the feed and take-up spools, the rear stretch being trained through the longitudinally extending guide, the stretches being spaced to receive a sheet of paper therebetween, and means carried by the longitudinally extending guide for separating the sheets of paper one from the other, said means including rearwardly extending arcuate fingers disposed under the platen roller, a plate carried by the rear terminals of the fingers, and right-angularly extending attaching ears.
2. The combination with a typewriter including a frame, a reciprocating carriage on said frame, a platen roller rotatably mounted upon the carriage, spaced ribbon guides on said carriage, and feed and take-up spools on the frame, of means for making an original and a duplicate copy on the typewriter including an endless ribbon, guide rollers for the ends of said ribbon, one of said rollers being spring-pressed, a longitudinally extending ribbon guide mounted upon said carriage in front of the platen roller and in rear of the first mentioned ribbon guides, the ribbon including front and rear stretches, the front stretch being threaded through the first mentioned guides and around the feed and take-up spools, the rear stretch being trained through the longitudinally extending guide, the stretches being spaced to receive a sheet of paper therebetween, and means carried by the longitudinally extending guide for separating the sheets of paper one from the other, said means including rearwardly extending arcuate fingers disposed under the platen roller, a plate carried by the rear terminals of the fingers, right-angularly extending attaching ears, the longitudinal ribbon guide having slots formed in its front and rear faces, and a thin flexible strip carried by the inner face of the front wall of the longitudinal guide covering the slot in said front wall.
3. The combination with a typewriter including a frame, a reciprocating carriage on said frame, a platen roller rotatably mounted upon the carriage, spaced ribbon guides on said carriage, and feed and take-up spools on the frame, of means for making an original and a duplicate copy on the typewriter including, an endless ribbon, guide rollers for the ends of the endless ribbon carried by and extending beyond the sides of the frame, a longitudinally extending ribbon guide mounted upon said carriage in front of the platen roller and in rear of the first mentioned ribbon guides, guide rollers on said carriage disposed between the ribbon guides on the carriage and the guide rollers on the frame, the ribbon including front and rear stretches, the front stretch being threaded through the first mentioned guides and over the feed and take-up spools, the rear stretch being trained through the longitudinally extending guide on the carriage and over the guide rollers on the carriage.

WILLIAM H. SCHMIDT.
